The ornamental design for the tile spacer, as shown and described herein.

DESCRIPTION

FIG. 1 is a perspective view of my tile spacer in accordance with my invention;

FIG. 2 is a top view thereof;

FIG. 3 is a side view thereof;

FIG. 4 is a side view opposing that of FIG. 3;

FIG. 5 is another side view thereof;

FIG. 6 is a side view opposing that of FIG. 5;

FIG. 7 is a perspective view of my tile spacer in accordance with another embodiment thereof;

FIG. 8 is a top view thereof;

FIG. 9 is a side view thereof;

FIG. 10 is a side view opposing that of FIG. 9;

FIG. 11 is another side view thereof; and,

FIG. 12 is a side view opposing that of FIG. 11.

The broken line portions of the figure drawings are included to show portions of the article that form no part of the claimed design.
